SYSTEM OF MOTOR CONTROL

Filed May 2, 1918

UNITED STATES PATENT OFFICE.

EDWIN S. MATTHEWS, OF NEW YORK, N. Y.

SYSTEM OF MOTOR CONTROL.

Application filed May 2, 1916. Serial No. 232,072.

To all whom it may concern:

Be it known that I, EDWIN S. MATTHEWS, a citizen of the United States of America, and a resident of the borough of Manhattan, city, county, and State of New York, have invented certain new and useful Improvements in Systems of Motor Control, of which the following is a full, clear, and exact description, reference being had to 10 the accompanying drawings, which form a part of this specification.

My present invention relates to the control of electric motors, and particularly to their control under all possible conditions 15 of operation, whether the motor be operated with a light or heavy load or no load whatsoever; or whether it be overhauled and made to act as a generator either by a large or a small force, or in the case of alternation or fluctuation of the conditions of operation, and this invention provides a novel system of motor control.

The objects of this invention are in general to secure increased economy of operation and greater refinement and precision of control particularly at slow speeds and at or near the point of coming to rest of the motor and its attached apparatus, either automatically or by manipulation or by a 25 combination of these methods.

Among useful applications of this invention are heavy gun pointing, heavy turret moving, elevator car operation, or any use of electric power where the apparatus attached to the motor is desired to come to rest accurately and precisely at some given point, either automatically or by manipulation, irrespective of conditions of loading overhauled 35 or momentum of attached apparatus.

An exemplifying embodiment of this invention is herein shown in connection with an elevator apparatus of the well known traction type which affords conditions of both dragging and overhauling variable 40 loading and of mass momentum in stopping; and increased efficiency in the practical use of this elevator apparatus is obtained in economy of current consumption and by the precision with which the car is 45 brought to a stop at landings avoiding loss of time in adjusting levels, which is of frequent occurrence in high speed service, as is well known.

An illustration of the present practice in

electric motor control, the defects of which are obviated by this invention, is shown in the following data from the recent test of a modern elevator equipment operating in a prominent building in one of our eastern cities and is as follows:—

Current consumed to run lightly loaded car slowly when being slowed down and adjusted to landing 109 amperes.

Current consumed to run same load about 600' per minute 55 amperes.

Current consumed to run lightly overhauled car when being slowed down and adjusted to landing 76 amperes.

Current generated in running same over-haul about 600' per minute 18 amperes.

Speeds of lightly loaded and lightly overhauled car when run slowly and adjusted to landing 72 feet per minute and 153 feet per minute respectively.

Obviously this variation in speed is increased when the apparatus is more heavily loaded.

The want of accurate control and the wastage of current above shown may be understood by referring to the fact that the ratio of speed of a given dragging load to that of the same overhauling load in the case of a motor with a given shunt and series armature circuit and a constant field strength is:—

$$\text{Ratio} = \frac{P - C_A R_L}{P + C_A R_L}$$

where P =the potential of the incoming line, C_A =the armature current and R_L =the resistance in the line in series with the armature.

Hence, when as in present systems any given point of speed control calls for a certain fixed armature series and shunt circuit it becomes necessary, in order to maintain even a remote correspondence between dragging and overhauling speed so as to have any certainty of control whatever, to make the line resistance small which unavoidably causes wastage of operating current.

One object of this invention is to decrease the speed variation above referred to and thus provide greater certainty of control and at the same time to avoid the wastage of operating current above mentioned.

Another object of this invention is to

keep the control of the apparatus in the hands of the operator to the maximum practicable extent in the case of a hand operated adjusting control.

5 Another object of this invention is to give a sufficient certainty of accurate speed control under all circumstances so as to permit automatic adjustment of the apparatus to a fixed point with a high degree of 10 precision, and to provide an apparatus in which both manual and automatic control may be employed together.

Other features and objects of this invention will become manifest to those skilled in 15 the art as its typical embodying instrumentalities and its operation are later explained and its novel features are pointed out in the claims.

A brief general description of the apparatus herein shown, as embodying this invention, is here given for facilitating the apprehending of its details hereinafter more fully described; in which:-

An elevator car and its counterweight are 25 driven directly from a slow speed armature in the well known manner of the traction elevator.

The motor is a direct current reversible shunt wound motor, the highest speed of the 30 apparatus being attained by a weakening of its field.

A friction brake is employed to hold the apparatus at rest and to stop it after electrical conditions for its slowest speed have been 35 established.

Two sets of speeds are provided, viz, running speeds, and adjusting speeds.

A manual controlling switch is employed having in the case of this typical illustration 40 two running speed points of control and three adjusting speed points of control, and giving control of the direction of motion. Obviously the number of speeds and their controlling points in the operator's switch 45 may be varied, if desired.

In addition to this and cooperating with it an automatic stop control is provided to bring the apparatus to rest in this case at either of two fixed points viz, the upper or 50 the lower terminal landings.

The apparatus is started and brought to its various running speeds in this embodiment of the invention by the employment only of series armature resistance and variation of field strength.

The adjusting speeds in this embodiment of the invention are obtained only by the employment of a fixed armature series resistance and a variable shunt resistance the 60 latter being doubly variable; both from the particular speed adjusting point of control employed and from the armature current conditions.

A comparatively weak shunt field is constantly maintained upon the motor which is

automatically strengthened when the motor is started, weakened at its highest speed and automatically strengthened whenever an armature shunt circuit is in action whether the armature is or is not connected to the main 70 line.

The armature starting resistance, which is a series resistance, is cut out gradually, upon starting the motor, by a series of switches which short-circuit sections of this 75 resistance successively as the growing counter-electromotive force of the accelerating armature develops, finally removing all of it; at which time the elevator assumes its slowest running speed.

The armature adjusting shunt resistance is governed by two sets of switches one set being operated by circuits from the adjusting speed contacts of the control switch which bring this armature shunt resistance into action only when a certain fixed series 80 armature resistance has been put in circuit, and which permit certain of this shunt resistance to come into action; the extent of which is automatically modified by the polarized regulator which governs the other set of switches acting upon this resistance.

An auxiliary switch, retaining the manual controlling switch contacts which actuate the reversing switches for use during the 85 adjustment period, and obviating all waste of current through the armature shunt circuit in starting the motor, is also provided in this embodiment of the invention.

The reversing switches make and break 100 the circuit of the main line through the armature and govern its direction of rotation and the operating circuit of these switches is provided with automatically actuated switches, which, while preventing too sudden reversal of the armature circuit, yet keep a reversing switch always at the operator's disposal.

The exemplifying structure herein shown 110 is illustrated by a diagrammatic drawing, the usual conventionalities being therein employed, and this structure will now be described more fully in detail, reference being had to the drawing, in which:-

Current supply enters the apparatus at the signs + and - at the middle left hand top and bottom of the drawing.

10 represents a motor armature with a sheave concentric therewith and directly attached thereto over which passes a wire cable 11 attached at one end to an elevator car 12 and at the other end to a counterweight 13, the two latter being driven from the armature by friction between the wire cable and the sheave in any of the well known traction 120 manners.

The armature brushes are shown at 14 and 15.

A friction brake is shown at 16.

The hand control switch is shown at the 130

left hand of the drawing for the sake of clearness in showing its circuits; this switch in practice being of course located within the car and its circuits connected to the apparatus through a flexible cable attached thereto.

The running speed and adjusting contacts shown on the left hand of this switch are for upward motion of the elevator and those at the right hand for downward motion; + supply entering it from + main 17 through conductor 18 and contacts 19 and 20.

As the operation of the up and down control circuits is identical with the exception that they are arranged to be opened separately by the automatic stop device with reference to the direction in which the apparatus is moving, and that they bring into action either the up motion or down motion reversing switch respectively according to the direction of motion desired; and further since the operation of these reversing switches is the same except that they reverse the direction of the current through the armature, only one set of these control circuits will be designated by numbers and described in detail and the accompanying operation of the apparatus described; thus avoiding complicating the drawing by an excessive number of reference numerals, although the complete circuits are shown on the drawing and may be traced through, if desired.

The control circuits for upward motion will be thus used for the purpose of this description.

A circular segmental contact strip 21 is swung about the center 22 manually by the handle 23 engaging the speed point contacts 24 and 25 for starting the apparatus and for producing low and high running speeds respectively and contacts 26, 27 and 28 for producing adjusting speeds; the first motion of the segment 21 over contacts 26, 27 and 28 in starting the apparatus producing no effect beyond the removal of the armature shunt circuit; whereas later, after the apparatus has been started, the release of contacts 26, 27 and 28 introduces and modifies the armature shunt circuit for the purpose of adjustment, as will later be described in detail.

The apparatus will now be described in its operation of upward motion during its starting, speed adjusting and stopping from the manipulation of the operator's switch and its stopping from the automatic stop device mentioned; and in this connection its circuits and instrumentalities will be described in detail.

During the period of rest but one circuit is in operation, viz, that which maintains its weakened field circuit which starts from + main 17 at 29 traverses conductor 30 diverging at point 31 and passing through

conductor 32 resistance 33 and shunt field 34 reaches the — main 36 at 35.

In starting the apparatus no immediate effect is produced by the first closing of contacts 19, 28, 27 and 26 by the operator's control switch as the circuit from 28 is open at point 42 after traversing conductor 281, and the circuit from 27 is open, including open point 38, after traversing the conductors 271, automatic stop contact 272, 271 coil of switch 273, conductor 242627 and 37;—and the circuit from 26 is likewise open at the same point after traversing similarly numbered paths and the common conductor 242627.

The circuit from running speed control point 24 of the operator's switch through coil 241 would also be open at the same point where it not for the fact that when speed point 24 is reached by the operator's switch the up reversing switch 39 is closed, which closes contact 38, and starts the apparatus in the following manner.

+ supply from main 17 through conductor 18 contact 19 segment 21 contact 24 conductors 241, 244 lower coil of auxiliary switch 40 to the — supply line 36 thus actuating auxiliary switch 40 closing the follow up spring contacts 41 and 42 with the plate of the switch, which plate comprises two insulated halves connected by conductors to reversing switch control contacts 28 and 50 respectively of the operator's switch thus completing in this case a circuit 17, 18, 19, 21, 28, 281, 42 through conductor 283 the actuating coil of up reversing switch 39, conductor 284 the back contacts of down reversing switch 43 to — supply main 36.

The potential now upon the armature causes the holding coil 451 of auxiliary switch 40 to retain its plate against follow up contacts 41 and 42 as long as any appreciable potential remains upon the armature; (circuit from one end of coil 451 through 171 to brush 14, and from the other end of coil through 362 to point 493 conductor 361 resistance 44 and 172 to brush 15) and when this potential vanishes to still keep these contacts closed until the vacuum air dash pot 461 has allowed them to separate; this dash pot being constructed in a well known manner so as to allow prompt closing action of switch 40 but to retard its opening, although other forms of retarding apparatus may be used, if desired; thus retaining the operator's reversing switch contacts in service as long as they can be required for adjusting purposes.

The closure of reversing switch 39 closes contact 38 with the — supply main 36 thus completing the circuits of operator's switch contacts 24, 26 and 27 through all the actuating coils of the armature shunt circuit controlling switches 243, 263 and 273 as will readily be understood from the preceding tracing of

the typical circuit at speed point 27 up to the point 38, which at that time was open.

Thus the armature shunt circuit is immediately removed at the outset of the starting of the apparatus.

The energizing of the conductor 37 also causes two other operations incident to the starting of the apparatus to be effected, viz, the removal of the friction brake 16 and the 10 strengthening of the motor field 34.

The former takes place through the action of a circuit through the actuating coil of the brake proceeding from + supply at conductor 30 at point 373 and passing through conductor 371 now bearing the - potential.

The latter occurs as the result of a circuit from the end of conductor 30 (+) through conductor 376 the actuating coil of field control switch 45, resistance 375 and conductor 20 374 to conductor 37 (-); thus actuating switch 45 and short circuiting field resistance 33.

The armature resistance 44 (series resistance only being in circuit) is now automatically short-circuited gradually; for the opening of switch 243 (armature shunt maker) closes a circuit at its lower contacts from brush 14 conductor 171, 173 through lower contacts of switch 243 conductor 174 through 20 all the actuating coils of the series-resistance controlling switches 175, 176, 177 and 178 common conductor 179 conductor 172 to the opposite brush of the armature 15.

These coils and switches respond to the rising armature potential successively in the order of their designating numbers in a well known manner gradually short-circuiting the armature series starting resistance 44 until the final action of switch 178 has removed it entirely.

It will be noted that this armature series starting resistance cannot be removed until the armature shunt circuit is broken.

The elevator now attains its slow running speed.

If the attempt should be made to suddenly reverse the apparatus by reversing the operator's switch so that it drops contact 19 and engages contact 20 and speed contact 50 or 51 (for down motion) the apparatus will not reverse until its speed is sufficiently diminished so that reversal may be effected without throwing undue current upon the armature, which is accomplished in the following manner:

It has been mentioned that the circuit for the actuating coil of the up reversing switch 39 which has been operated in this description passes through the back contacts of down reversing switch 43. So likewise the actuating circuit of the down reversing switch 43 passes through the back contacts of up reversing switch 39 and these contacts have been opened when the up reversing switch 39

was closed by the raising of plate 46 away 68 from these contacts.

This plate is loose upon spindle 47, being raised by the head 48 of said spindle, and now having been raised up to within the influence of magnet 49 (which is preferably 70 provided with iron return magnet line flux circuit enclosure as shown in the drawing in order that its magnetic force may be concentrated and intensified) it will remain held there by even a slight potential upon the 75 armature thus keeping the actuating circuit of the down reversing switch 43 broken until the armature potential has decreased sufficiently to permit of its reversal even if reversing switch 39 be opened.

The circuit of this holding coil of magnet 49 proceeds from the lower end of the coil through conductors 491 and 171 to brush 14 and from the upper end of the coil through conductor 362 joining conductor 361 at point 80 493 thence through resistance 44 and conductor 172 to brush 15.

The broken actuating circuit of the down reversing switch 43 proceeds from + main 17 conductor 18 contact 20 segmental plate 90 21 contact 50 conductor 501 plate of switch 40, contact 41 conductor 503 through actuating coil of switch 43 conductor 504 to the lower broken contact of switch 39; which contact will become closed and complete the 95 actuating circuit of switch 43, as soon as the armature potential has sufficiently fallen, by the dropping of plate 46 from the weakened holding coil of 49 whereupon the actuating circuit of the down reversing switch 43 will 100 be completed to the - main 36 in an obvious manner, and permit reversal to take place.

Since the similar plate governing the actuating circuit of the up reversing switch 39 (operated in this illustrative operation—see 105 circuit previously traced) has not been brought within the influence of its holding coil because the down reversing switch to which it is attached has not been operated, it is obvious that there will be no interference with the operator's control of the actuating circuit of the up reversing switch; and even if he should drop this switch and thus permit it to open he is enabled to pick it up again for use in adjusting the apparatus if he should so desire.

Thus the operator has a reversing switch always at his disposal for purposes of adjustment, and he is afforded maximum control of the apparatus as far as is consistent 110 with safety and economy of operation.

If the higher running up speed of the apparatus is desired the operator swings his controlling switch sufficiently to engage contact 25 of this switch whereupon the + current supply of this switch (already understood) passes through conductor 251 the upper (now closed) contacts of switch 178 con-

- tinuing on conductor 251 to the point 252; thus short circuiting the actuating coil of field control switch 45 upon the + main, as will be readily understood from the circuit 5 of this coil formerly traced. This causes switch 45 to open introducing the resistance 33 into the field circuit; thereby weakening the strength of the field and accelerating the apparatus to the higher running speed.
- 10 It will be noted that in case the operator had quickly moved his control switch to the high speed point 25 it would have been impossible to weaken the field of the motor until all the series starting resistance had been 15 removed from its armature circuit through the final action of switch 178 for until that time the high speed control circuit 251 remains broken at the upper contacts of switch 178.
- 20 Retracting the operator's switch so as to open high running speed contact 25 will slow the car down to its lower running speed by causing the field strengthening switch to close and cut out the resistance 33 from the 25 field circuit in a manner that is now obvious.
- Further retraction of the operator's switch, so as to additionally open running speed contact 24, but retaining adjusting speed contact 26 in use, will slow the car 30 down still further bringing its speed down to the rate of its highest adjusting speed for the armature shunt circuit will now be brought into action, and the armature series resistance will now be introduced, in a manner now readily understood, for:-
- The opening of control circuit 241 by this movement of the operator's control switch, de-energizes the actuating coil of the auxiliary switch 40, but this switch still remains 40 closed through the action of its holding coil as is obvious from the previous description of its operation and its circuits.
- Additionally the actuating coil of switch 243 (armature shunt maker) is de-energized 45 causing this switch to open its back contacts thus de-energizing all the series resistance control switches 175, 176, 177 and 178 (as will be understood from the previous description of their circuits and operation), 50 causing all of them to open thus introducing the armature series resistance 44 into the circuit of the armature with the main line.
- At the same time an armature shunt circuit is made at the upper contacts of this 55 switch 243 through brush 14 conductors 171, 173, upper contacts of switch 243, all of the armature shunt resistance 51, 52 and 53 (as switches 263 and 273 are now open) and conductor 54 to brush 15; except as to the extent 60 of the segments 51, 52 and 53 employed, which is modified by the action of switches 55 and 56 that govern the working portions of these shunt resistance segments.
- In the position of the apparatus shown in
- the drawing (which is that of medium regulation as will be later fully explained) it will be noted that switch 56 being open exercises no effect upon any portion of armature shunt resistance sections, but that switch 55 being closed short circuits a portion of each of the 65 segments 51, 52 and 53 by the closure of its contacts upon conductors 601 and 611 leading to points 60 and 61 in the shunt resistance respectively and the additional conductors 591 (leading to point 59 of section 51), 621 (leading to point 62 of section 52) and 641 (leading to point 64 of section 53) thus cutting out of service the portions 59-60 of section 51, 61-62 of section 52 and 61-64 of section 53, thereby reducing the working 70 shunt resistance to that included between points 57 and 59, 60 and 62, 66 and 64.
- This action of the apparatus, as shown by the position of switches 55 and 56 in the drawing is that of medium armature shunt 75 resistance and will be that occurring when the armature is being traversed by no current or by a small current resulting either from dragging or overhauling load as will be understood from an examination of the 80 operation of these switches 55 and 56, which will now be explained.
- Obviously if switch 55 were to be opened by the energization of its actuating coil its short-circuiting effect as shown in the position of the drawing would cease and all the armature shunt resistance comprising the total resistance of sections 51, 52 and 53 would be in circuit which would give the action of maximum armature shunt resistance 100 occurring when the armature is traversed by a considerable current resulting from a dragging load as will later be made evident by the elucidation of the action of the polarized regulator in controlling switches 105 55 and 56.
- Also obviously if switch 56 were to be closed by the energization of its actuating coil the armature shunt resistance would be short circuited still further than is shown 110 in the position of the drawing; for section 51 would lose portion 58-60; section 52 would lose portion 61-63; while section 53 would lose portion 61-65; thus establishing the condition of minimum armature shunt 115 resistance occurring when the armature is traversed by a considerable current caused by overhauling load as will be fully explained later.
- In this case point 58 is short circuited to 120 60 through conductors 581 and 601; point 61 is short circuited to 63 through conductors 611 and 631; and point 61 is short circuited to point 65 through conductors 611 and 651, 125 all the above mentioned conductors being closed at the contacts of switch 56 when it is closed.

It is to be noted that each and every one of

the sections of armature shunt resistance 51, 52 and 53 is separately governed as to working portions thereof by the action of switches 55 and 56 so that a proper governing effect is ensured whether one, more, or all of the sections 51, 52 and 53 is brought into action by the operator's control switch or by the automatic stop device.

In the examination of the operation of the polarized regulator to follow, it will also be noted that regulating effect is produced in this exemplification of the invention by the action of the current traversing the armature so that the regulation is equally effective and sensitive whether the potential of the armature be high or low and consequently irrespective of the number of sections or the quantity of armature shunt resistance in service or the operator's speed 20 point of control employed or the degree to which the automatic stop device may have been operated; so that the regulation continues effective during manual or automatic slow down either preparatory to a stop or 25 in and during the use of the adjusting speeds however low the speed of the apparatus may be brought.

The common drain conductor of the actuating coils of switches 55 and 56 is found in 30 conductor 5556 which joins the — main at 5557. A supply of actuating current from the + main 17 at point 29 is afforded the actuating coil of switch 55 through conductors 30, 553 switch 552 of the polarized regulator 67 whenever this switch is closed and conductor 551; while a similar supply is afforded the actuating coil of switch 56 from point 29 through conductors 30, 563, switch 562 of the polarized regulator 67 whenever 40 this switch is closed and conductor 561; hence whenever switch 552 is closed, switch 55 will be actuated and its contacts opened; and whenever switch 562 is closed switch 56 will be actuated and its contacts closed.

45 The polarized regulator, which will now be described, is actuated by an electric magnet 68 hereinafter designated as the armature magnet, energized by a coil 69 in the armature circuit which coil in this exemplification of the invention forms a part of armature conductor 171.

Hence the polarity of this armature magnet 68 is determined by the direction of the armature current, i. e. by whether the current is toward or from the armature; while 55 its power is dependent upon the amount of such current and when no current is passing through the armature, the armature magnet 68 will not be energized.

50 Two other coils are shown upon this armature magnet, which are wound at proper polarity, being placed in series and in this case closed circuited through an adjustable resistance at 71.

These coils are deadening coils and their office is to prevent too sudden a response of the magnetism of 68 to peaks of current instantaneously occurring and but momentary in duration when armature speed conditions are abruptly changed, and thus to avoid super-sensitivity in the action of the regulator.

Other retarding means either electrical or mechanical such as variations of dash-pot constructions may be used for this purpose 75 and the sensitiveness of response to either rise or fall of magnetization or to both (as in the present exemplification) may be used, if desired, without departing from the spirit of this invention; while the apparatus is operative and efficient without any retardation of deadening; although to avoid unnecessary action and wear of parts it is preferred to use a deadening feature.

This electro-magnet 68 is preferably provided with an outside enclosing iron cylindrical shell or bars 72 for the return circuit of magnetic lines and this shell is provided with inner re-entrant bosses 73 and 74 in order to ensure uniformity of magnetic field 90 and distribution of magnetic flux between the ends of the inner core of the armature magnet 70 and these bosses 73 and 74; and the ends of 70 project suitably beyond the enclosing coils so as to avoid any bunching 95 or undue concentration of magnetic lines in any portion of their path under any circumstances; and the magnet coils and the enclosing iron shell are constructed suitably to produce this effect.

100 This produces a uniform state of magnetic flux (similar to that inside and near the center of a magnetizing helix) between 70 and 73 and 74 in which spaces the actuating electromagnets of the switches 552 and 562 vibrate in their control of these switches.

The switches 552 and 562 are shown as obtuse angled elbow-switches swinging about the pivots 75 and 76 respectively and in the drawing each is shown in open position with their actuating electro-magnets and coils 79, 80 and 81, 82 respectively in a position of repose with each of these electromagnets close to its re-entrant boss 73 and 74 respectively, being held in this 115 position by some action of gravity and by the tension of their regulating springs 77 and 78 respectively. Obviously either switch will be closed whenever the attraction of the armature magnet draws its respective 120 actuating magnet to itself.

In this embodiment of the invention all the magnets of the polarized regulator become energized as soon as current is turned upon the armature, and remain operative 125 as long as the armature is electrically excited.

Since the energizing coil of the armature

magnet 68 is in armature conductor 171 it is energized according to the amount of the armature current and its polarity is reversed by reversal of the apparatus.

- 8 The polarity of actuating magnets 79 and 81 is correspondingly reversed as will be seen by noting their circuits both of which are supplied from conductors 361 and 171 which receive reversible full line potential.
- 10 The circuit of actuating coil 80 joins conductor 361 above the right hand end of the coil through a flexible conductor 83 while coil 82 is provided with a similar flexible conductor 84 also similarly joining conductor 361.
- 15 The other ends of these coils are also provided with flexible conductors 85 and 86 joining a common conductor 87 which joins 171 through points 88 and 89.

- 20 If it is desired to retain full potential upon the actuating coils 80 and 82 also during the complete period of dynamic braking (after the reversing switch has been dropped) their conductors are supplied with a reversible 25 full line potential through contacts attached to holding on plate 46 of the up reversing switch and its companion plate of the down reversing switch in a similar manner, now easily understood, instead of directly from 30 the reversing switch itself as herein illustrated for the sake of simplicity.

The energizing coils of actuating magnets 79 and 81 are oppositely wound so that each presents the same polarity toward the 35 armature magnet and each to the other. All polarities of all these magnets are reversed upon reversal of the apparatus. Thus the inductive effect of magnetic lines arising from the actuating magnets alone and solely, 40 since they are of equal strength, practically vanishes.

The action of governing the speed of the apparatus while its adjusting speed contacts are in use will now be explained by 45 the aid of a concrete illustration whereupon the mode of operation of the apparatus in that respect will become obvious.

Its operation will be examined when the operator has slowed down to adjusting speed 50 contact 26, previously mentioned, the effect of which has been heretofore described with the exception of the governing of the extent of the armature shunt circuit through the action of the polarized regulator.

55 In the upward motion of the car the actuating magnets of the polarized regulator will be supposed to present, each of them, an N pole to the armature magnet and to each other, while the armature magnet is so wound as to present an N pole to actuating magnet 81 of switch 562 and an S pole to actuating magnet 79 of switch 552 while its armature is receiving current or working under a dragging load;—and an S pole to

magnet 81 of switch 562 and an N pole to 65 actuating magnet 79 of switch 552 while generating current or working under an overhauling load;—while under conditions of no current passing through the armature or working with a practically balanced load, 70 the armature magnet will not be energized.

The condition of balanced loading will first be examined as that is the condition represented in the drawing.

While so running, the armature magnet 76 68 is de-energized and neither actuating magnet 79 or 81 will be moved, the switches 55 and 56 will both be unactuated, as shown in the drawing, and the medium amount of armature shunt resistance employed which 80 has been heretofore described in detail.

At the instant the shunt armature resistance is introduced a peak of generated armature current will occur, due to the slower speed conditions thus imposed, but it 85 will, in the case of small momentum, be nearly instantaneous; as it is due solely to the momentum of the apparatus there being no actual overhauling load present to produce any generative effect;—and the polarized regulator as usually adjusted will not in such case respond to it. It will, however, as usually adjusted, respond to large momentum; armature magnet 68 being temporarily energized by the generated current, 90 thus momentarily closing switch 56, its effect being merely to check excessive momentum; for the generated armature peak current will suddenly fall as the motor slows down, de-energizing magnet 68, thus opening 100 switch 56, and so bring the apparatus automatically to the position shown in the drawing, which provides a standard speed responding to the use of adjusting speed contact 26.

Now in case the apparatus has been operating under a considerable overhauling load, magnet 81 has been actuated, closing switch 562, energizing the actuating coil of switch 56 thus closing the latter establishing the 110 condition of minimum armature shunt resistance as will be understood from previous explanations; and the tendency of the apparatus to assume unduly rapid overhauling speed during the use of adjusting speed contact 26 will be corrected, and the apparatus brought to standard speed.

If, on the contrary, the apparatus has been operating under a considerable dragging load, magnet 79 has been actuated, 120 closing switch 552, energizing the actuating coil of switch 55, thus opening the latter establishing the condition of maximum armature shunt resistance as will also be readily understood from previous explanations; and the tendency of the apparatus to assume unduly slow dragging speed during the use of speed contact 26 will be corrected,

and the apparatus brought to standard speed.

If excessive momentum is present when an adjusting speed contact is brought into use while a dragging load is slowed down, switch 55 may be closed for an instant, and in the case of great excess momentum switch 56 may also be closed for an instant, but these effects will be exceedingly short and will merely aid in checking the momentum, in which the dragging load itself will assist; and upon this momentum being checked the apparatus will automatically again assume the position of maximum shunt resistance.

This feature of the action of the polarized regulator being understood it is also now obvious that when adjusting speed contacts are abruptly advanced to higher speed, and the armature draws considerable current from the line, the higher armature shunt resistance circuits may be momentarily established; as for illustration, the switch 55 will in some cases open its contacts and thus aid the apparatus in "picking up" or accelerating the load promptly; after which the proper equilibrium condition is automatically effected.

The polarized regulator thus aids in accelerating or retarding the speed of the motor moved apparatus, and also establishes a standard speed for a given speed control contact.

In the embodiment of the invention here-with illustrated two standardizations of adjusting speeds are shown independent of the balanced load standard adjusting speed; one for dragging load and one for overhauling load; but obviously standard speeds may also be provided for light and heavy loading, if desired, for additional switches may be employed, similar to and operating in the same general manner as those illustrated; but responding to the degree of dragging or overhauling load so that the speed variation during the use of adjusting speed contacts may be reduced to any limit desired; and economy of operation increased.

The construction herein shown is, however, by judicious proportioning of resistance and proper adjustment of responsiveness, capable of fulfilling nearly all practical requirements.

A slower adjusting speed is obtained by still further retracting the operator's switch so as to open contact 26 (the operation of the apparatus accompanying the employment of which as an adjusting speed control contact has been described) and retaining in service contact 27 and 28 as adjusting speed contacts.

In this case switch 263 of the armature shunt resistance is closed by the de-energization of its actuating coil through the severance of its supply current which is de-

rived from contact 26 of the operator's switch now opened.

This short circuits section 51 of the armature shunt resistance leaving sections 52 and 53 alone in service, the working amount of which sections is governed by the polarized regulator as is now understood, from the previous tracing of the circuits involved; thus diminishing the amount of armature shunt resistance employed while the armature series resistance remains unchanged and establishing a slower adjusting standard speed of the apparatus than that which was afforded while the higher adjusting speed contact 26 was in use.

Still further retraction of the operator's switch so as to employ only contact 28 will cause a still further reduction in the standard adjusting speed of the apparatus, bringing it in this case, to its slowest adjusting speed that employed preliminary to making a stop.

In this operation switch 273 is closed in a manner exactly similar to the closing of switch 263 just above described and sections 51 and 52 of the armature shunt resistance are now short-circuited leaving in service only working segments of section 53, thus again diminishing the armature shunt resistance, while the armature series resistance remains unchanged thus establishing the slowest standard adjusting speed; for the reversing switch still remains closed through the action of contact 28 of the operator's switch the actuating circuit of which has been heretofore traced and described.

The circuits from the operator's control switch employed for obtaining these slower adjusting speeds are shown in the drawing, but will not be traced in detail as they will be readily understood from the tracing of the circuits employed with adjusting speed contact 26 to which they are similar and similarly numbered; contact 26 controlling switch 263 and contacts 27 controlling switch 273, while contact 24 controls switch 243, which latter makes or breaks the armature shunt resistance circuit.

Continued retraction of the operator's switch which opens contact 28, and brings that switch to the position shown in the drawing, deprives the actuating coil of the reversing switch of its current (as will be understood from its circuit previously traced) causing the reversing switch to open thus severing the armature main line current, and de-energizing the actuating coil of friction brake 19 (see its circuit previously traced) thus applying the friction brake; while working segments of section 53 of the armature shunt resistance being still in circuit act as a dynamic brake thus bringing the apparatus to a stop.

It will now be obvious to those skilled in

- the art that by the use of this invention economy of operation may be preserved and at the same time adjusting speed of the apparatus may be made controllable and much 5 slower than has been heretofore practicable, which is of importance when accuracy of stopping of the apparatus is desirable and especially so when this is to be accomplished automatically.
- 10 The application of this invention to one kind of automatic stopping of the motor driven apparatus is herewith illustrated, but its employment is obviously not limited to this particular manner of automatic stopping.
- 15 The apparatus for properly severing the control circuits so as to bring the elevator apparatus herein illustrated to rest accurately, at its upper and lower terminals of travel, is diagrammatically and conventionally shown in the drawing, beneath the operator's switch, in order to avoid complicating the circuits and to facilitate the reading of the diagram.
- 20 The stop from upward motion will be considered in detail, as the downward stop is similar thereto, and hence will be easily understood without detailed explanation after the upward stop is described.
- 25 The three pronged elbow lever 90 is located on the elevator car and swings about the pin 91 fixed thereon, automatically coming to the position of rest or no control, as shown in the drawing, when between terminals and outside of the influence of cam surfaces 92 and 93 which are respectively situated near the upper and lower landings respectively and within the limits of car travel.
- 30 As the car approaches the upper landing the cam 92 engages the roller 94 upon the pin 95 at or near the end of the pendant arm of the elbow lever 90 and the continued upward motion of the car causes cam 92 to push the pin 95 to the left (as shown in the drawing) thus swinging elbow lever 90 and raising the arm 101, which engages successively the pins 96, 97, 98, 99 and 100; thus successively opening the up motion contacts 252, 242, 262, 272, and 282; the timing of these successive engagements being preferably adjusted so as to cause the apparatus to assume its standard adjusting equilibrium speed for each severed circuit before the next succeeding circuit is opened and in any event to assume its lowest standard adjusting speed while contact 282 is closed and just before its opening causes the line current to be severed from the armature and stops the apparatus.
- 35 This lowest standard adjusting speed (through the use of contact 282) being low, the momentum of the apparatus is slight; hence upon severance of the armature line circuit by the opening of contact 282 caused by the continued motion of the car and the consequent opening of the reversing switch applying the dynamic and the friction brakes, the apparatus is brought to an accurate stop.
- 40 A special adjustment of the working segments of section 53 of the armature shunt resistance (which is the only segment in use preparatory to a stop) is made by increasing the relative proportion of the resistance of segment 53 short-circuited by switches 55 and 56, so that the speed of the dragging load is somewhat greater than that of the overhauling load; and consequently the influence of the load to either diminish 45 or prolong (as the case may be) the distance traveled by the apparatus in coming to a stop when the armature circuit is severed, is compensated. However, when additional segments of the armature shunt resistance are employed, the amounts of working resistance are so proportioned that the speeds of the dragging or the overhauling load are equally affected, being brought to practically the same standard speed.
- 45 Additional dynamic braking force, beyond that afforded by segment 53 of the armature shunt resistance, may be employed, if desired, in various manners, as for illustration;—by placing an additional segment of 50 armature shunt resistance in parallel with 53 whenever the reversing switches are open, and accurate results are obtained by causing the working amounts of all or any dynamic braking resistance to be governed 55 through switches 55 and 56 or other similar switches (after the main line current is severed from the armature) through the polarized regulator—in the manner heretofore described; but this will seldom be desirable on account of the low speed obtained from the lowest speed adjusting control contact.
- 50 Whenever armature shunt resistance is in service, whether for speed adjusting or for dynamic braking, the current traversing this 60 resistance passes through actuating coil 102 of field strengthening switch 103 as coil 102 forms a part of armature shunt conductor 173 causing switch 103 to be closed during the armature shunt action thus ensuring a 65 strong field upon the motor even after switch 45 has been caused to open by the opening of the reversing switch.
- 55 The contacts of the down motion control 70 circuits are undisturbed after automatic upward stoppage and consequently the apparatus may be reversed.
- 60 It will be seen that certainty and precision of operation of the polarized regulator is ensured by electrical as well as mechanical 75 means; for whenever the armature of the motor is taking no current the open position of both switches 552 and 562 is due not only to the action of their mechanical adjusting weights or springs (as is usual in switches) 80

but also to the electrical repulsion of the respective polarities of their actuating magnets and whenever electrical conditions cause either of the switches to come into action, the other switch is withheld from action by an increased repulsion as well as by the usual mechanical means.

It will also be seen that the action of these switches is equally positive when the potential of the armature is low (at slow speeds) and when consequently a rise or fall of a few volts potential causes a large proportional variation in speed thus ensuring positive control of the slowest speeds of the apparatus. This arises from causing the standardization of speed to be effected from the action of the armature current and not from the potential present at the armature brushes, which potential, on account of resistance control effected by current actuated means, is kept substantially constant for any given speed condition as called for by the particular adjusting speed contact which is in use; this potential being fixed for each adjusting speed contact according to the speed which such contact is designed to effect. Since proper regulative modifications of armature resistance are fixed by current conditions (irrespective of whatever adjusting speed contact may be in use) no rearrangement of these regulative conditions becomes necessary when different potentials are applied to the armature by changing the speed contact in use.

While the motor is running from the use of the running speed contacts, with no resistance in its armature circuit it exemplifies a motor (electrically considered) operating with a circuit imposing substantially fixed speed condition; for but slight variation in its speed is produced by mechanical force applied to its armature to hinder or to help its rotation, although current conditions are varied by such application. However, when operating from the use of its adjusting speed contacts, without the potential regulator and its connected instrumentalities, it exemplifies a motor (electrically considered) operating in a circuit imposing variable speed conditions for in this case on account of the presence of armature resistance in its circuit, its speed and current conditions are both materially varied by the application of mechanical force to help or to hinder armature rotation, and this is accompanied by a variation in armature potential.

The effect of the polarized regulator and its connected instrumentalities is to vary the resistance in a variable speed imposing circuit, according to the amount and direction of current passing through the armature and thereby control, within comparatively narrow limits, the variation of the armature potential; and to do this with certainty independently of this armature potential,

whether it be high (in the case of the high adjusting speeds) or low (in the case of the slow adjusting speeds). Further illustration of the independence of this control from the armature potential is seen when it causes that potential to become lower in the case of action of the motor as a dynamo and it is generating current, than when acting as a motor and it is receiving current from the supply, as shown when the resistance segments of section 53 are adjusted to produce compensated stopping, as previously mentioned; thus arbitrarily reversing the potentials normally developed in a circuit of this character.

Also further on account of the nature of the magnetic circuit employed in the polarized regulator, which avoids inductive concentration of magnetic lines these switches 552 and 562 will promptly release and automatically open whenever the electrical condition of the armature calls for such action; the mutual repulsion of their respective actuating magnets contributing to this result.

In the embodiment of the invention herewith illustrated a reversible motor is shown, and the actuation magnets 80 and 81 are polarized reversibly by the electric current energizing them, according to the direction of armature rotation.

If a motor revolving in one direction only is employed, reversible polarization of these actuation magnets becomes unnecessary, and in such case, if desired, they may be made of hard steel permanently polarized and of a suitable fixed strength.

This construction embodying this invention herewith illustrated contains other novel and useful features in addition to the polarized regulator which latter, as well as other features of the invention, may be employed in connection with other arrangements of circuits, switches, field, armatures, and associated and cooperating parts and instrumentalities and—

Many variations in the construction and details and the location and relative arrangement of parts would readily suggest themselves to those skilled in the art to which this invention relates and still fall within the spirit and scope of my invention; hence I do not desire to be limited to the exact construction herein set forth; but having explained the principles of my invention, and a preferred form of apparatus embodying it, and—

Having described the function, purpose and mode of operation of such apparatus what I claim as new and of my own invention, and desire to secure by Letters Patent of the United States is,—

1. The combination of a motor, conductors carrying current therefor, a circuit for said motor including means whereby variable speed conditions are imposed thereupon,

- and automatic means constructed and arranged to vary said circuit oppositely so as to raise or lower the potential applied to the armature of said motor in accordance with increase or decrease of armature current flow. 5
2. The combination of a motor, conductors carrying current therefor, a circuit for said motor armature containing armature series resistance and armature shunt resistance therein, and automatic means constructed and arranged to oppositely vary the resistance of said circuit in accordance with increase or decrease of armature current flow. 10
3. The combination of a motor, conductors carrying current therefor, a circuit for said motor including means whereby variable speed conditions are imposed thereupon, and automatic means constructed and arranged to vary said circuit in accordance with the amount and direction of current flow through the armature of said motor and independently of the armature potential. 15
4. The combination of a motor, conductors carrying current therefor, a circuit for said motor armature containing armature series resistance and armature shunt resistance therein, and automatic means constructed and arranged to oppositely vary the resistance of said circuit in accordance with increase or decrease of armature current flow and independently of the armature potential. 20
5. The combination of a motor, conductors carrying current therefor, a circuit for said motor armature containing series resistance and armature shunt resistance therein, and automatic means constructed and arranged to oppositely vary the resistance of the shunt portion of said circuit in accordance with increase or decrease of armature current flow. 25
6. The combination of a motor, an operator's switch for starting and controlling the speed circuits of the motor, conductors carrying current for said motor, conductors carrying current for said operator's switch, a speed circuit for the motor armature supply which contains armature shunt resistance and armature series resistance therein, a switch for closing the circuit of the motor armature current supply, an additional switch for breaking the armature shunt portion of said circuit, and means for so actuating said switches from the operator's starting switch that the armature supply circuit cannot be actuated to close without breaking the said armature shunt circuit. 30
7. The combination of a motor, conductors carrying current therefor, a plurality of circuits for the armature of said motor one of which when in use includes means whereby a variable speed condition is imposed upon the motor, electrically actuated switches for selectively opening or closing these said circuits from the operator's
- switch, operating circuits for actuating said switches, conductors carrying current therefor, and an automatically actuated switch constructed and arranged to vary the resistance of the variable speed condition circuit in accordance with current conditions of the armature. 70
8. The combination of a motor, conductors carrying current therefor, a plurality of circuits for the armature of said motor one of which when in use includes means whereby a variable speed condition is imposed upon the motor, electrically actuated switches for selectively opening or closing these said circuits from the operator's switch, operating circuits for actuating said switches, conductors carrying current therefor, and an automatically actuated switch constructed and arranged to vary the resistance of the variable speed condition circuit in accordance with current conditions of the armature, and independently of the armature potential. 80
9. The combination of a motor, conductors carrying current therefor, a plurality of circuits for the armature of said motor, one of which contains armature series resistance and armature shunt resistance, electrically actuated switches for selectively opening or closing the said circuits from the operator's switch, operating circuits for actuating said switches, conductors carrying current therefor, and an automatically actuated switch constructed and arranged to vary armature circuit resistance in accordance with current conditions of the armature. 90
10. The combination of a motor, conductors carrying current therefor, a plurality of circuits for the armature of said motor, one of which contains armature series resistance and armature shunt resistance, electrically actuated switches for selectively opening or closing the said circuits from the operator's switch, operating circuits for actuating said switches, conductors carrying current therefor, and an automatically actuated switch constructed and arranged to vary armature circuit resistance in accordance with current conditions of the armature and independently of the armature potential. 105
11. The combination of a motor, conductors carrying current therefor, an armature circuit for said motor containing armature series resistance and armature shunt resistance, and an automatic electro-magnetically actuated switch responsive to the armature current flow only, constructed and arranged to oppositely vary the resistance in said circuit in accordance with increase or decrease of said flow. 115
12. The combination of a motor, conductors carrying current therefor, an armature circuit for said motor containing armature series resistance and armature shunt resist- 120
13. The combination of a motor, conductors carrying current therefor, an armature circuit for said motor containing armature series resistance and armature shunt resist- 125
14. The combination of a motor, conductors carrying current therefor, an armature circuit for said motor containing armature series resistance and armature shunt resist- 130

- ance, and an automatic electro-magnetically actuated switch responsive to current flow into the armature, said switch being constructed and arranged to increase the said shunt resistance when so responding.
13. The combination of a motor, conductors carrying current therefor, an armature circuit for said motor containing armature series resistance and armature shunt resistance, and an automatic electro-magnetically actuated switch responsive to a certain amount of current flow into the armature and constructed and arranged to increase the said shunt resistance, when so responding; said switch being also conversely responsive to a current flow into the armature of less amount than the aforesaid certain amount above mentioned and when so conversely responding to decrease said shunt resistance.
14. The combination of a motor, conductors carrying current therefor, an armature circuit for said motor containing armature series resistance and armature shunt resistance, and an automatic electro-magnetically actuated switch actuated by current flowing outward from the armature, said switch being constructed and arranged to decrease the said shunt resistance when so responding.
15. The combination of a motor, conductors carrying current therefor, an armature circuit for said motor containing armature series resistance and armature shunt resistance, and an automatic electro-magnetically actuated switch responsive to a certain amount of current flow outward from the armature and constructed and arranged to decrease the said shunt resistance when so responding; said switch being also conversely responsive to a current flow outward from the armature of less amount than the aforesaid certain amount above mentioned and when so conversely responding to increase the said shunt resistance.
16. The combination of a motor, conductors carrying current therefor, an armature circuit for said motor containing armature series resistance and armature shunt resistance, and an automatic electro-magnetically actuated switch responsive to current flow into the armature, said switch being constructed and arranged to increase the said shunt resistance when so responding and an additional automatic electro-magnetically actuated switch responsive to current flow outward from the armature, said switch being constructed and arranged to decrease the said shunt resistance when so responding.
17. The combination of a motor, conductors carrying current therefor, an armature circuit for said motor containing armature series resistance and armature shunt resistance, and an automatic electro-magnetically actuated switch responsive to a certain amount of current flow into the armature and constructed and arranged to increase the
- said shunt resistance, when so responding; said switch being also conversely responsive to a current flow into the armature of less amount than the aforesaid certain amount above mentioned and when so conversely responding to decrease said shunt resistance, and an additional automatic electro-magnetically actuated switch responsive to a certain amount of current flow outward from the armature and constructed and arranged to decrease the said shunt resistance when so responding; said switch being also conversely responsive to a current flow outward from the armature of less amount than the aforesaid certain amount above mentioned and when so conversely responding to increase the said shunt resistance.
18. In a system of motor control, the combination with the current supply mains thereof of an electro-magnet located in the armature circuit said electro-magnet being constructed and arranged so as to be polarized correspondingly to the direction of armature current flow, a movable magnet polarized suitably for attraction to the said electro-magnet during armature current flow in a certain direction only, and a switch actuated by the said movable magnet for varying the speed controlling circuits of said motor control system while the current supply mains are transmitting current to the apparatus.
19. In a system of motor control, the combination with the current supply mains thereof of an electro-magnet located in the armature circuit said electro-magnet being constructed and arranged so as to be polarized correspondingly to the direction of armature current flow, a movable magnet polarized suitably for attraction to the said electro-magnet during armature current flow in a certain direction and repelled therefrom during armature current flow in the opposite direction, and a switch actuated by the said movable magnet for varying the speed controlling circuits of the motor control system oppositely according to the attraction or repulsion of said movable magnet while the current supply mains are transmitting current to the apparatus.
20. In a system of motor control, the combination with the current supply mains thereof, of an armature magnet, located in the armature circuit, said armature magnet being constructed and arranged so as to be polarized correspondingly to the direction of armature current flow, and energized correspondingly to the amount of such flow, a movable magnet polarized suitably for attraction to said armature magnet during armature current flow in a certain direction and of a certain amount, and withdrawn therefrom during such directional current flow of less than the aforesaid certain amount, and a switch actuated by said mov-

- able magnet for varying the speed controlling circuits of the motor control system oppositely according to the attraction or withdrawal of said movable magnet, 6 while the current supply mains are transmitting current to the apparatus.
21. In a system of motor control, the combination of an armature magnet, located in the armature circuit, said armature magnet being constructed and arranged so as to be polarized correspondingly to the direction of armature current flow and energized correspondingly to the amount of such flow, a series resistance and a shunt resistance in the armature circuit, a movable magnet polarized suitably for attraction to said armature magnet during armature current flow in a certain direction and of a certain amount, and withdrawn therefrom during such directional current flow of less than the aforesaid certain amount and a switch actuated by said movable magnet for varying the resistance in the armature circuit oppositely according to the attraction or withdrawal of said movable magnet.
22. In a system of motor control, the combination of an armature magnet, located in the armature circuit, said armature magnet being constructed and arranged so as to be polarized correspondingly to the direction of armature current flow and energized correspondingly to the amount of such flow, a series resistance and a shunt resistance in the armature circuit, a movable magnet polarized suitably for attraction to said armature magnet during armature current flow in a certain direction and of a certain amount, and withdrawn therefrom during such directional current flow of less than the aforesaid certain amount and a switch actuated by said movable magnet for varying the aforesaid shunt resistance oppositely according to the attraction or withdrawal of said movable magnet.
23. In a system of motor control, the combination of an armature magnet located in the armature circuit, said armature magnet being constructed and arranged so as to be polarized correspondingly to the direction of armature current flow and energized correspondingly to the amount of such flow, a series resistance and a shunt resistance in the armature circuit, a movable magnet polarized suitably for attraction to said armature magnet during current flow into the armature of a certain amount, and withdrawn therefrom during such directional current flow of less than the aforesaid certain amount and a switch actuated by said movable magnet for increasing the said shunt resistance upon the attraction of the movable magnet to the armature magnet and for decreasing the said shunt resistance upon withdrawal of the movable magnet from the armature magnet.
24. In a system of motor control, the combination of an armature magnet located in the armature circuit, said armature magnet being constructed and arranged so as to be polarized correspondingly to the direction of armature current flow and energized correspondingly to the amount of such flow, a series resistance and a shunt resistance in the armature circuit, a movable magnet polarized suitably for attraction to said armature magnet during current flow outward from the armature of a certain amount and withdrawn therefrom during such directional current flow of less than the aforesaid certain amount and a switch actuated by said movable magnet for decreasing the said shunt resistance upon the attraction of the movable magnet to the armature magnet and for increasing the said shunt resistance upon withdrawal of the movable magnet from the armature magnet.
25. In a system of motor control, the combination of an armature magnet, located in the armature circuit, said armature magnet being constructed and arranged so as to be polarized correspondingly to the direction of armature current flow and energized correspondingly to the amount of such flow, a series resistance and a shunt resistance in the armature circuit, a movable magnet polarized suitably for attraction to said armature magnet during current flow into the armature of a certain amount, and withdrawn therefrom during such directional current flow of less than the aforesaid certain amount and a switch actuated by said movable magnet for increasing the said shunt resistance upon the attraction of the movable magnet to the armature magnet and for decreasing the said shunt resistance upon withdrawal of the movable magnet from the armature magnet; with a second movable magnet polarized suitably for attraction to said armature magnet during current flow outward from the armature of a certain amount and withdrawn therefrom during such directional current flow of less than the aforesaid certain amount, and an additional switch actuated by said second movable magnet for decreasing the said shunt resistance upon the attraction of said second movable magnet to the armature magnet and for increasing the said shunt resistance upon withdrawal of said second movable magnet from the armature magnet.
26. In a system of motor control, a motor, a speed controlling circuit for said motor, current supply mains therefor, a regulating electro-magnet in the armature circuit provided with a magnetic flux path concentrating its magnetic lines upon an actuation area within said path, and distributing said magnetic lines substantially uniformly within said actuation area, and a polarized actuating member constructed and arranged to

move in said actuation area responsively to the polarity and degree of magnetization of the said regulating electro-magnet and a switch operated by said actuating member for modifying the speed controlling circuit of said motor control system while the current supply mains are transmitting current to the apparatus.

27. In a system of motor control, a motor, 10 a speed controlling circuit for said motor, current supply mains therefor, a regulating electro-magnet in the armature circuit consisting of a magnetizing coil, an internal iron core and an external iron jacket there- 15 for constructed and arranged so as to absorb substantially all the magnetic flux arising from the energization of said coil, projections upon said core and said jacket ap- proaching each other but leaving between 20 them an air-gap so proportioned as to concentrate the magnetic flux therewithin and a polarized actuating member constructed and arranged to move in said air-gap re- 25 sponsively to the polarity and degree of magnetization of the said regulating elec- 30 tro-magnet, and a switch operated by said actuating member for modifying the speed controlling circuit of said motor control sys- tem while the current supply mains are transmitting current to the apparatus.

28. The combination with an electric motor of reversing switches, interlocking means operated by said reversing switches whereby the closing of either switch pre- 35 vents the closing of the other, and electro- magnetic means permanently connected to the armature of said motor for retaining said interlocking means operative until the motor is substantially at rest.

40 29. In a system of motor control the combination with an electric motor of electro- magnetic reversing switches therefor, means connected with each one of the reversing switches whereby closing of either switch 45 prevents the electro-magnetic closing of the other, and additional electro-magnetic means whereby the said prevention of the closing of said other switch continues operative until the motor speed is substantially reduced ir- 50 respective of any opening of either reversing switch.

30. In a system of motor control the combination with an electric motor of reversing switches therefor, an actuating electro-magnet associated with each switch, an individual operating circuit for each one of said actuating electro-magnets, a separate switch associated with each one of said reversing switches in each of said operating circuits whereby the closing of either one of said reversing switches opens the operating circuit of the other reversing switch and a holding electro-magnet permanently connected to the armature of said motor for re-

taining such said circuit open until the 65 motor speed is substantially reduced.

31. In a system of motor control the combination with an electric motor of reversing switches therefor, an actuating electro-magnet associated with each one of said reversing switches, a holding electro-magnet associated with each one of said reversing switches and connected to the armature brushes, an individual operating circuit for each one of the said actuating electro-magnets, a switch in each one of said operating circuits having an iron holding portion thereupon, whereby the closing of either one of said reversing switches opens the operating circuit of the other reversing switch and brings said iron holding portion within the magnetic influence of said holding electro-magnet.

32. In a system of motor control the combination with a motor, a current supply 85 therefor, an armature speed circuit for said supply containing armature series resistance and armature shunt resistance therein, an operator's switch for starting said motor control system into operation and controlling its speed circuits, a switch for breaking said armature shunt resistance path, a switch for connecting the current supply to said armature circuit, and switches for automatically, and gradually cutting out the 95 armature series resistance of said circuit path upon the connection of the supply thereto; of means for so actuating said switches from the said operator's switch that the armature supply circuit cannot be 100 actuated to close without breaking the said armature shunt resistance circuit path.

33. In a system of motor control the combination with a motor, a current supply 105 therefor, an armature circuit path containing armature series resistance and armature shunt resistance therein, an electro-magnetic switch which when actuated breaks the armature shunt resistance path, an electro- 110 magnetic switch which when actuated connects the current supply to the armature circuit, automatic switches for gradually cutting out the series resistance from the armature circuit path upon the connection of the supply thereto and the breaking of 115 the armature shunt resistance circuit path, an operator's switch for starting and ad- 120 justing said motor, a current supply for said operator's switch, said switch having a fixed position wherein none of the above mentioned armature current controlling switches are actuated, an adjusting position near said fixed position and a starting position more remote therefrom; circuits from said starting position actuating the above 125 mentioned switch for connecting supply current to the armature circuit and said above mentioned switch for breaking the

armature shunt resistance circuit, and circuits from said adjusting position for retaining the armature current supply switch in actuated position.

34. In a system of motor control the combination with a motor, a current supply therefor, an armature circuit path containing armature series resistance and armature shunt resistance therein, an electro-magnetic switch which when actuated breaks the armature shunt resistance path, an electro-magnetic switch which when actuated connects the current supply to the armature circuit, automatic switches for gradually cutting out the series resistance from the armature circuit path upon the connection of the supply thereto and the breaking of the armature shunt resistance circuit path, an operator's switch for starting and adjusting said motor, a current supply for said operator's switch, said switch having a fixed position wherein none of the above mentioned armature current controlling switches are actuated, an adjusting position near said fixed position and a starting position more remote therefrom; and an additional adjusting position between the aforesaid positions; circuits from said starting position actuating the above mentioned switch for connecting supply current to the armature circuit and said above mentioned switch for breaking the armature shunt resistance circuit, and circuits from said adjusting position for retaining the armature current supply switch in actuated position, and circuits from said additional adjusting position for varying the resistance in the armature circuit and for retaining the armature current supply switch in closed position.

35. In a system of motor control the combination with a motor, a current supply therefor, an armature circuit path containing armature series resistance and armature shunt resistance therein, an electro-magnetic switch which when actuated breaks the armature shunt resistance path, an electro-magnetic switch which when actuated connects the current supply to the armature circuit, automatic switches for gradually cutting out the series resistance from the armature circuit path upon the connection of the supply thereto and the breaking of the armature shunt resistance circuit path, an operator's switch for starting and adjusting said motor, a current supply for said operator's switch, said switch having a fixed position wherein none of the above mentioned armature current controlling switches are actuated, an adjusting position near said fixed position and a starting position more remote therefrom; circuits from said starting position actuating the above mentioned switch for connecting supply current to the armature circuit and said above mentioned switch for breaking the armature shunt resistance circuit, and circuits from said adjusting position for retaining the armature current supply switch in actuated position, and circuits from said additional adjusting position for varying the resistance in the armature circuit and for retaining the armature current supply switch in closed position.

above mentioned switch for breaking the armature shunt resistance circuit, and circuits from said adjusting position for retaining the armature current supply switch in actuated position, and switches for varying the resistance in the armature circuit automatically in accordance with armature current conditions.

36. In a system of motor control the combination with a motor, a current supply therefor, an armature circuit path containing armature series resistance and armature shunt resistance therein, an electro-magnetic switch which when actuated breaks the armature shunt resistance path, an electro-magnetic switch which when actuated connects the current supply to the armature circuit, automatic switches for gradually cutting out the series resistance from the armature circuit path upon the connection of the supply thereto and the breaking of the armature shunt resistance circuit path, an operator's switch for starting and adjusting said motor, a current supply for said operator's switch, said switch having a fixed position wherein none of the above mentioned armature current controlling switches are actuated, an adjusting position near said fixed position and a starting position more remote therefrom; and an additional adjusting position between the aforesaid positions; circuits from said starting position actuating the above mentioned switch for connecting supply current to the armature circuit and said above mentioned switch for breaking the armature shunt resistance circuit, and circuits from said adjusting position for retaining the armature current supply switch in actuated position, and circuits from said additional adjusting position for varying the resistance in the armature circuit and for retaining the armature current supply switch in closed position, and switches for varying the resistance in the armature circuit automatically in accordance with armature current conditions.

37. In a system of motor control the combination with a motor, a current supply therefor, a switch for connecting current supply to the armature circuit, an electro-magnet for actuating said switch, a circuit for carrying actuating and energizing current supply for said electro-magnet, a switch controlling said actuating and energizing current supply circuit and means for holding said last mentioned switch closed during the presence of armature potential.

38. In a system of motor control the combination with a motor, a current supply therefor, a switch for connecting current supply to the armature circuit, an electro-magnet for actuating said switch, a circuit for carrying actuating and energizing current supply for said electro-magnet, a switch

- controlling said actuating and energizing current supply circuit, means for closing said last mentioned switch, and means for holding it closed during the presence of armature potential. 5
39. In a system of motor control the combination with a motor, a current supply therefor, a switch for connecting current supply to the armature circuit, an electro-magnet for actuating said switch, a circuit for carrying energizing current supply for said electro-magnet, a switch controlling said energizing current supply circuit, means for holding said last mentioned switch closed 10 during the presence of armature potential, and a retarding device for delaying its opening. 15
40. In a system of motor control the combination with a motor, a current supply therefor, a switch for connecting current supply to the armature circuit, an electro-magnet for actuating said switch, a circuit for carrying energizing current supply for said electro-magnet, a switch controlling said energizing current supply circuit, means for closing said last mentioned switch, means for holding it closed during the presence of armature potential, and a retarding device 20 for delaying its opening. 25
41. The combination of a motor, conductors carrying current supply therefor, a circuit for said motor armature containing armature series resistance, and armature shunt resistance therein, and automatic means constructed and arranged to vary said circuit so as to maintain substantially the same potential upon the armature under variations in its current conditions. 30
42. The combination of a motor, conductors carrying current supply therefor, a circuit for said motor armature containing armature series resistance and armature shunt resistance therein, and automatic means constructed and arranged to vary said shunt circuit so as to maintain substantially the same potential upon the armature under variations in its current conditions. 45
43. The combination of a motor, conductors carrying current supply therefor, a plurality of circuits for said motor each circuit imposing a different speed condition upon said motor, means for connecting the motor to either one of said circuits, an armature series resistance and an armature shunt resistance in one of the said circuits, and automatic means constructed and arranged to vary the last mentioned circuit so as to maintain substantially the same potential upon the armature under variations in its current conditions. 50
44. The combination of a motor, conductors carrying current supply therefor, a plurality of circuits for said motor each circuit imposing a different speed condition upon said motor, means for connecting the 55
- motor to either one of said circuits, an armature series resistance and armature shunt resistance in one of the said circuits and automatic means constructed and arranged to vary the shunt resistance of said last mentioned circuit so as to maintain a higher potential upon the armature under variations in its current conditions. 60
45. The combination of a motor, conductors carrying current supply therefor, a circuit for said motor armature containing armature series resistance, and armature shunt resistance therein, and automatic means constructed and arranged to vary said circuit so as to maintain a higher potential upon the armature when it is receiving current from the supply than when it is generating current. 75
46. The combination of a motor, conductors carrying current supply therefor, a circuit for said motor armature containing armature series resistance and armature shunt resistance therein, and automatic means constructed and arranged to vary said shunt circuit so as to maintain a higher potential upon the armature when it is receiving current from the supply than when it is generating current. 80
47. The combination of a motor, conductors carrying current supply therefor, a plurality of circuits for said motor each circuit imposing a different speed condition upon said motor, means for connecting the motor to either one of said circuits, an armature series resistance and an armature shunt resistance in one of the said circuits, and automatic means constructed and arranged to vary the last mentioned circuit so as to maintain a higher potential upon the armature when it is receiving current from the supply than when it is generating current. 85
48. The combination of a motor, conductors carrying current supply therefor, a plurality of circuits for said motor each circuit imposing a different speed condition upon said motor, means for connecting the motor to either one of said circuits, an armature series resistance and an armature shunt resistance in one of the said circuits and automatic means constructed and arranged to vary the shunt resistance of said last mentioned circuit so as to maintain a higher potential upon the armature when it is receiving current from the supply than when it is generating current. 90
49. In a system of motor control the combination of a motor, a current supply therefor, an armature circuit path containing armature series resistance and armature shunt resistance therein, an electro-magnetic switch which when actuated connects the current supply to said armature circuit path, an operator's switch for adjusting and stopping said motor; said operator's switch hav- 100

- ing a fixed position wherein said electro-magnetic switch is deprived of energizing current; thereby depriving the armature of current supply, and an additional position provided for said operator's switch next to the first named fixed position, a supply of current for said operator's switch, a circuit from a contact closed by the said operator's switch when in said additional position holding the said electro-magnetic switch in actuated position, and automatic means constructed and arranged to vary the armature circuit so as to maintain a higher potential upon the armature when it is receiving current from the supply than when it is generating current.
50. In a system of motor control the combination of a motor, a current supply therefor, an armature circuit path containing armature series resistance and armature shunt resistance therein, an electro-magnetic switch which when actuated connects the current supply to said armature circuit path, an operator's switch for adjusting and stopping said motor; said operator's switch having a fixed position wherein said electro-magnetic switch is deprived of energizing current; thereby depriving the armature of current supply, and an additional position provided for said operator's switch next to the first named fixed position, a supply of current for said operator's switch, a circuit from a contact closed by the said operator's switch when in said additional position holding the said electro-magnetic switch in actuated position, and automatic means constructed and arranged to decrease the resistance in the shunt portion of the armature circuit as the current received by the armature from the supply decreases and to increase said resistance in the shunt portion of the armature circuit as said received current increases so as to maintain a higher potential upon the armature when it is receiving current from the supply than when it is generating current.
51. In a system of motor control the combination of a motor, a current supply therefor, an armature circuit path containing armature series resistance and armature shunt resistance therein, an electro-magnetic switch which when actuated connects the current supply to said armature circuit path, an operator's switch for adjusting and stopping said motor; said operator's switch having a fixed position wherein said electro-magnetic switch is deprived of energizing current; thereby depriving the armature of current supply, and an additional position provided for said operator's switch next to the first named fixed position, a supply of current for said operator's switch, a circuit from a contact closed by the said operator's switch when in said additional position holding the said electro-magnetic switch in

actuated position, and automatic means constructed and arranged to increase the resistance in the shunt portion of the armature circuit as the current generated by the armature decreases and to decrease said resistance as said generated current increases, so as to maintain a higher potential upon the armature when it is receiving current from the supply than when it is generating current.

52. In a system of motor control the combination of a motor, a current supply therefor, an armature circuit path containing armature series resistance and armature shunt resistance therein, an electro-magnetic switch which when actuated connects the current supply to said armature circuit path, an operator's switch for adjusting and stopping said motor; said operator's switch having a fixed position wherein said electro-magnetic switch is deprived of energizing current; thereby depriving the armature of current supply, and an additional position provided for said operator's switch next to the first named fixed position, a supply of current for said operator's switch, a circuit from a contact closed by the said operator's switch when in said additional position holding the said electro-magnetic switch in actuated position and automatic means constructed and arranged to decrease the resistance in the shunt portion of the armature circuit as the current received by the armature from the supply decreases, and to increase said resistance as said received current increases, and to increase the resistance in the shunt portion of the armature circuit as the current generated by the armature decreases and to decrease said resistance as said generated current increases so as to maintain a higher potential upon the armature when it is receiving current from the supply than when it is generating current.

53. In a system of motor control the combination of a motor, current supply means therefor, a speed controlling circuit for said motor, a regulating electro-magnet in the armature circuit, and provided with a magnetic flux path concentrating its magnetic lines substantially uniformly within said actuation area, and a polarized actuation member movably located within said actuation area, with a retarding device constructed and arranged to delay the responsive motion of said actuation member to a change of magnetic flux of said regulating electro-magnet, and a switch operated by said actuation member for modifying the speed controlling circuit of said motor control system while the current supply mains are transmitting current to the apparatus.

54. In a system of motor control the combination of a motor, a speed controlling circuit for said motor, a regulating electro-

magnet in the armature circuit consisting of a magnetizing coil, an internal iron core and an external iron jacket therefor constructed and arranged so as to absorb substantially all magnetic flux arising from the energization of said coil, projections upon said core and said jacket approaching each other but leaving between them an air-gap so proportioned as to concentrate the magnetic flux therein, a polarized actuation member movably located within said air-gap, with a retarding device constructed and arranged to delay the responsive motion of said actuation member to a change of magnetic flux of said regulating electro-magnet and a switch operated by said actuation member for modifying the speed controlling circuit of said motor control system, while the current supply mains are transmitting current to the apparatus.

55. In a system of motor control the combination with a motor, conductors carrying current supply therefor, a switch for closing the armature current supply, a circuit path for the motor armature which contains armature shunt resistance and armature series resistance therein, an additional switch for breaking the armature shunt portion of said path and means independent of the armature supply circuit operated by the closure of said first mentioned switch to effect the operation of the said second mentioned switch.

56. In a system of motor control the combination with a motor, conductors carrying current supply therefor, an electro-magnetic switch for closing the armature current supply, a circuit path for the motor armature which contains armature shunt and armature series resistance therein, an additional electro-magnetic switch for breaking the armature shunt portion of said path, a contact closed by the closure of said first mentioned switch, and a circuit therefrom independent of the armature supply circuit effecting the operation of the said second mentioned switch.

57. The combination with a motor, conductors carrying current supply therefor, an electro-magnetic switch for closing and opening the armature current supply, an electro-magnetically actuated friction brake for the armature, an armature circuit which contains armature series resistance and armature shunt resistance therein, automatic means constructed and arranged to maintain substantially the same potential upon the armature under variations in its current condition, and means operated by the closure of the said first mentioned switch to release said electro-magnetic friction brake, and to apply said brake upon its opening.

58. The combination with a motor, conductors carrying current supply therefor, an electro-magnetic switch for closing and

opening the armature current supply, an electro-magnetically actuated friction brake for the armature, an armature circuit which contains armature series resistance and armature shunt resistance therein, automatic means constructed and arranged to maintain a higher potential upon the armature when it is receiving current from the supply than when it is generating current, and means operated by the closure of the said first mentioned switch to release, said electro-magnetic friction brake and to apply said brake upon its opening.

59. In a system of motor control, the combination of a motor, conductors carrying current therefor, a circuit for the armature of said motor containing armature series resistance and armature shunt resistance therein, automatic means constructed and arranged to oppositely vary the resistance of said circuit in accordance with increase or decrease of armature current flow and automatic armature connected means operative upon a predetermined amount of revolution of said armature to break the said armature circuit.

60. In a system of motor control the combination of a motor, conductors carrying current therefor, a plurality of circuits for said motor each circuit imposing a different speed condition upon said motor, means for connecting the motor to either one of said circuits, and armature series resistance and an armature shunt resistance in one of said circuits, automatic means constructed and arranged so as to oppositely vary the resistance in said last mentioned circuit in accordance with increase or decrease of armature current flow, and automatic armature connected means operative upon a predetermined amount of revolution of said armature to change the existing circuit connection of the motor to a lower speed circuit connection.

61. In a system of motor control, the combination of a motor, conductors carrying current therefor, a circuit for said motor including means whereby variable speed conditions are imposed thereupon, and automatic means constructed and arranged to oppositely vary said circuit, so as to raise or lower the potential applied to the armature of said motor in accordance with increase or decrease of armature current flow, and automatic means operative upon a predetermined amount of revolution of said armature, to break the armature circuit.

62. In a system of motor control, the combination of a motor, conductors carrying current therefor, a plurality of circuits for said motor each imposing a different speed condition upon said motor, means for connecting the motor to either one of said circuits, one of which includes means whereby variable speed conditions are imposed on

the motor, means constructed and arranged to oppositely vary the latter of said circuits so as to raise or lower the potential applied to the armature of said motor automatically in accordance with increase or decrease of armature current flow, and automatic means operative upon a predetermined amount of revolution of said armature to change the existing circuit connection of the motor to a lower speed circuit connection.

63. In a motor control system a regulator for automatically controlling variations of

armature potential whose actuating coil is placed so as to be in series with series armature resistance, and in shunt with shunt armature resistance during current flow into the armature; and in series with shunt armature resistance and in shunt with series armature resistance during current flow outward from the armature. ¹⁵
